UNITED STATES PATENT OFFICE.

ARCHEE H. BECHTOL, OF MEMPHIS, TENNESSEE, AND WALTER A. TRATSCH, OF CHICAGO, ILLINOIS.

TARGET FOR AMUSEMENT DEVICES.

Application filed November 30, 1923. Serial No. 677,738.

To all whom it may concern:

Be it known that we, ARCHEE H. BECHTOL and WALTER A. TRATSCH, both citizens of the United States, respectively residing at

5 Memphis, Shelby County, State of Tennessee, and Chicago, in the county of Cook and State of Illinois, have invented certain new and useful Improvements in Targets for Amusement Devices; and we do hereby 10 declare the following to be a full, clear, and exact description of the invention, such as will enable others skilled in the art to which it appertains to make and use the same.

This invention relates to targets for use 15 in amusement devices, and has for its object to provide a construction comparatively inexpensive to manufacture and more efficient in use than those which have heretofore been proposed.

20 With these and other objects in view, the invention consists in the novel details of construction, and combinations of parts more fully hereinafter disclosed and particularly pointed out in the claims.

25 This invention is especially adapted for use in connection with the amusement device disclosed and claimed in the patent granted to us on May 15, 1923, and numbered 1,454,947.

30 Referring to the accompanying drawings forming a part of this specification, in which like numerals designate like parts in all the views:

Figure 1 is a partial sectional view of a 35 target made in accordance with this invention;

Figure 2 is an elevational view of the stationary member of such a target;

Figure 3 is a view of a portion of the movable member of such a target;

Figure 4 is a side view of an amusement device with portions broken away to show the application of the invention thereto; and

45 Figure 5 is a sectional view of a pistol adapted to actuate the movable member of such a target.

In the drawings, 1 indicates the top frame member of an amusement device provided 50 with the slot 2 and supporting one edge of a transparent top through which the target may be viewed. 3 are the sides and 4 is the bottom member of the said device. Between the top frame member 1 and the bottom member 4 is the shelf 5 which is pro-

vided with the slot 6 positioned in line or registry with the slot 2 in the top member 1. The shelf 5 together with the top 1 forms the support for the target casing.

This said casing comprises a front plate 60 7 provided with the opening 8, through which the target may be seen. The said front plate 7 is further provided at its top and bottom edges with the flanges 9 and 10 respectively, and through these flanges are 65 cut the slots 12 and 13. The back of said casing comprises a non-yielding plate 14 likewise provided at its top and bottom edges with the flanges 15 and 16 respectively. The said flanges 15 and 16 are, however, shorter than the flanges 9 and 10, in order to provide a space between the front plate 7 and the back plate 14, when the casing is assembled. The casing is so made that the back and front members will closely fit 70 one within the other, and when the members are in such position, see Figure 1, the casing may be fastened to the top 1 and the shelf 5 by any means such as the screws 17. From Figure 1, it will be observed that the 75 slots 2, 6, 12 and 13 are so positioned in their respective members as to be in registry with each other when the parts are assembled, thus affording an unobstructed 80 passage for the movable target strip.

85 20 indicates a stationary target sheet which may be made of any relatively thin yieldable material, such as celluloid, and which is provided with any suitable score markings 21, upon one of its faces, such for 90 example as the well known bull's-eye. As clearly shown in Figure 1, this stationary target 20 is so positioned in back of and contacting with, the front plate 7, that the score markings 21 will be centered in the 95 opening 8 of the said front plate.

100 Behind this stationary target 20 is placed a sheet 25 of any copying medium, such for example as the well known carbon paper, and between this sheet 25 and the back plate 14 of the target casing is fed a strip 27 of movable targets. To insure the copying sheet 25 from being displaced, when the strip 27 is moved, the said copying sheet may be secured in any suitable manner 105 not shown, to the stationary target 20, or to the target casing.

110 The strip 27 of movable targets is of sufficient width to closely fit, but not bind in, the aforementioned slots 2, 6, 12 and 13, and

is preferably supplied in a roll 28 which may be conveniently mounted upon a shaft 29. The said shaft 29 may be rotated in any suitable manner, as by means of the 5 ratchet wheel 30 mounted on one end thereof and actuated through the medium of the spring controlled pawl 31 carried by the lever arm 32 fastened to one end of a pull rod 33 slidably supported by the 10 bracket 35, secured to the bottom 4 of the amusement device, all as clearly shown in Figure 1. To the other end of the rod 33 is fastened a wire 36 which extends to the front of the amusement device and terminates in a loop 37, which may be grasped by the fingers of the operator or may be looped over the hook 38, as best shown in Figures 4 and 5, on the trigger 39 of a pistol 40 adapted to fire balls at the target.

20 A spring 43 mounted on said pull rod 33 presses against the support 35 at one end and against a suitable stop such as the washer 44, held by the pin 45 at its other end. A pin 46 limits the movement of the rod 33 25 in its return direction, as will be seen in Figure 1.

On the strip 27 are successively printed, impressed, or otherwise suitably secured, in equal spaced relation, the score markings 30 50 of the exact same size and configuration as the score markings 21 on the stationary target 20. Between these markings 50 are also printed or impressed guide lines indicated in Figure 3 by the dotted line 51. 35 Mounted upon the upper side of the frame member 1, Figure 1, and extending longitudinally along one side of the slot 2 is an angle piece 55 provided with the sharpened upper cutting edge 56 constituting 40 a well known means whereby the external portion of the strip 27 may be severed from the said strip.

The score markings 50, as well as the guide 45 lines 51, are so spaced upon the target strip 27 that when one of the said guide lines registers with the cutting edge 56, the score markings 50 next below the said line will be in registry with the score markings 21 of the stationary target 20. That is 50 to say, if the target strip 27 be fed out of the slot 21 which it closely fits, and stopped when a guide line 51 shows along the cutting edge 56, then the lowermost point 57 and the extreme left point 58 of 55 the score markings 50 on the said strip will lie in the same horizontal and vertical planes as contain the lowermost point 59 and the furthermost left point 60 respectively, of the score markings 21 on the stationary target 20.

Tension may be applied to the roll 28 of movable targets, or to the strip 27 itself, in any suitable manner, such for example as by the spring clamps 65. An incline 65 66 provided with a guide groove 67 directs

the fired balls in a manner fully disclosed in our said patent above mentioned, to the funnel 68, communicating with the cylinder 69 of the pistol 40; all as will be clear from Figures 4 and 5. The pistol is recharged 70 by the revolution of the said cylinder by mechanism not shown but actuated by each pull of the trigger 39, all as will be clear from our said patent. The operation of the amusement device and target will be 75 clear from the foregoing; but may be briefly described as follows:

The operator aims the pistol 40 at the target and pulls the trigger 39, whereupon 80 a ball 100 fired from the said pistol strikes the stationary target 20 with considerable force. No mark, however, is left upon the said target sheet 20, but the force with which the ball is fired from the pistol is sufficient to cause the said ball, through the medium 85 of the yieldable sheet 20 and copying sheet 25, to impress a mark upon the movable target sheet 27 in a manner well understood. This mark of course will be exactly behind, or in registry with, the point of contact 90 made by the ball 100 with the stationary target sheet 20. Therefore, since the score markings 50 on the movable target sheet 27 are in registry with the score markings 21 on the stationary target sheet 20, as 95 heretofore explained, it follows that the mark made upon the said sheet 27 will record on the score markings 50 thereon, the point where the ball hit the target sheet 20.

The operator then pulls the trigger 39 again, whereupon another ball is fired by the pistol 40 at the target and, as above, makes a mark upon the movable target 27. 105 This operation is repeated until the operator has made all the shots to which he is entitled.

In some cases it may be desirable to automatically unwind a predetermined portion of the strip 27 from the roll 28 upon firing 110 each shot, and to this end the wire 36 may be looped over the hook 38 on the trigger, as indicated in dotted lines. When this is done, each pull of the trigger 39 causes the wire 36, through rod 33, arm 32, pawl 31, 115 and ratchet 30, to revolve the roll 28, thereby unreeling a section 70 of the movable target strip 27. This loosened section 70 does not affect the position of that portion of the strip 27 located within the target casting, since the tensioning means 65 are sufficient to prevent any accidental slippage. The amount of strip 27 unreeled by each 120 pull of the trigger may be varied according to the number of shots allowed to be fired 125 at the target. On the other hand, when it is not desired to thus automatically unwind the sheet 27 from the roll 28, the loop 37 may be unhooked from the trigger as illustrated in full lines, and in such case 130

said loop may be grasped by the hand and the pawl 31 and ratchet 30, thus operated. However, in most cases, the said pawl and ratchet need not be operated at all, as it 5 will suffice for the operator to merely pull the sheet 27 by hand out of the slot 2. That is, after the last shot has been fired, the operator grasps the stub, or end of the strip 27, extending above the top frame member 10 1, and pulls the said strip out of the frame until the next guide line 51 registers with the cutting edge 56. He thereupon tears off, in the well known manner, the portion of the said strip 27 above this line and which 15 has upon it the record of his shots. The device is then ready for use by the next operator.

It is obvious that those skilled in the art may vary the details of construction as well 20 as the arrangement of parts, without departing from the spirit of the invention, and therefore it is not desired to be limited to the above disclosure except as may be required by the claims.

25 What we claim is:

1. In an amusement device, the combination of a firing means; a target provided with a movable portion; connections between said movable portion and said firing 30 means; means associated with said movable portion adapted to leave an imprint on said movable portion when a shot strikes said target; and means whereby said movable portion may be positioned with reference to 35 said target.

2. In an amusement device, the combination of a firing means comprising a pistol provided with a trigger; a target provided with a movable portion; connections between said movable portion and said firing 40 means; means associated with said movable portion adapted to leave an imprint on said movable portion when a shot strikes said target; and means whereby said movable portion may be positioned with reference to 45 said target.

3. In an amusement device, the combination of a firing means; a target provided with a movable portion comprising a sheet 50 of flexible material having score markings spaced predetermined distances apart; connections between said movable portion and said firing means; means associated with said movable portion adapted to leave an imprint 55 on said movable portion when a shot strikes said target; and means whereby said movable portion may be positioned with reference to said target.

4. In an amusement device, the combination of a firing means; a target provided with a movable portion; connections comprising a feed mechanism between said movable portion and said firing means; means associated with said movable portion 65 adapted to leave an imprint on said movable

portion when a shot strikes said target; and means whereby said movable portion may be positioned with reference to said target.

5. In an amusement device, the combination of a firing means; a target provided 70 with a movable portion; connections between said movable portion and said firing means; means comprising a sheet of copying paper associated with said movable portion adapted to leave an imprint on said movable portion when a shot strikes said target; and means whereby said movable portion 75 may be positioned with reference to said target.

6. In an amusement device, the combination of a firing means; a target provided 80 with a movable portion; connections between said movable portion and said firing means; means associated with said movable portion adapted to leave an imprint on said 85 movable portion when a shot strikes said target; means to hold said movable portion in said target; and means whereby said movable portion may be positioned with reference to 90 said target.

7. As a new article of manufacture, the herein described new target for use in amusement devices, the same comprising a stationary flexible front sheet; a copying sheet disposed behind said front sheet and 95 adapted to make a record when said front sheet is struck; and a movable sheet disposed behind said copying sheet and adapted to receive a record from the latter when said front sheet is struck.

8. As a new article of manufacture, the herein described new target for use in amusement devices, the same comprising a stationary flexible front sheet provided with 105 suitable score markings; a copying sheet disposed behind said front sheet and adapted to make a record when said front sheet is struck; and a movable sheet provided with score markings disposed behind said copying sheet and adapted to receive a record from 110 the latter when said front sheet is struck.

9. As a new article of manufacture, the herein described new target for use in amusement devices, the same comprising a stationary flexible front sheet provided with 115 score markings; a copying sheet disposed behind said front sheet and adapted to make a record when said front sheet is struck; a movable sheet provided with score markings adapted to register with said first named 120 score markings disposed behind said copying sheet and adapted to receive a record from the latter when said front sheet is struck; and means for readily severing said movable sheet.

In testimony whereof we affix our signatures.

ARCHIE H. BECHTOL,
WALTER A. TRATSCH.
